UNITED STATES PATENT OFFICE.

ARTHUR F. BLASIAR, OF GUILFORD, NEW YORK.

TORPEDO.

Application filed February 28, 1925. Serial No. 12,445.

This invention relates to improvements in torpedoes and more particularly to improvements in the propulsion mechanism therefor.

It is well-known to those familiar with this subject that submarine torpedoes are driven by means of two oppositely rotating propellers at the after-end thereof which are in turn driven by oppositely rotating turbines connected therewith through intervening reduction gearing.

The present invention contemplates a drive mechanism of the above general character in which a single vertically disposed turbine is intended to operate either as a reduction turbine or as a combined impulse and reaction turbine, the gases in the latter case being only partially expanded in the first stage nozzles and the expansion progressing throughout the remaining stages to back pressure. The pressure drop can be controlled in the desired manner by proper design of the blading whereby the turbine may be operated at a speed sufficiently low to permit direct connection to the propeller shafts thus eliminating the gear train heretofore considered necessary.

It is, therefore, one of the objects of the present invention to provide a mechanism of the above general character characterized by simplicity and compactness, reduction of weight and cost and possibilities of increased power, efficiency and reliability.

A further object is to provide a gear mechanism of the above character having an improved oil circulating system for properly lubricating the transmission during the run of the torpedo.

Other objects will be in part obvious and in part hereinafter pointed out in connection with the accompanying sheets of drawings wherein is shown a preferred embodiment of the invention and in the several views of which corresponding reference characters indicate similar parts throughout.

In these drawings, Figure 1 is a vertical sectional view taken through the turbine longitudinally of the axis of the torpedo, certain parts being shown diagrammatically.

Figure 2 is an elevational view of the turbine with certain parts broken away or in section for the sake of clearness.

Figure 3 is a detail view of a part of the turbine wheel.

Referring now to the drawings in detail and more particularly to Figure 1, 5 indicates the outside shell of the torpedo near

the forward end of the midship section or just aft of the compartment holding the air flask fuel reservoirs and combustion flask.

This section contains a supporting spider 60 or plate having adjacent thereto a second spider 7 secured thereto by means of spacing members 8.

Interposed between the two spiders are the turbine wheels, one of which 10 is provided with a plurality of pockets or blades 11 adapted to coat alternately with pockets 12 carried by the other wheel 13. The turbine 10, which may be considered the driving turbine, is rotatably connected by an inlet 70 pipe 14 with the main source of supply pipe 15, the latter being connected directly with the combustion flask to which the air, fuel and water are supplied and ignited in the usual well-known manner.

It will also be noted that the driving wheel 10 is mounted directly upon shaft 16 while the driven wheel or turbine 13 is connected with the concentric shaft 17. The wheels or turbines rotating in opposite directions 80 will, of course, drive these shafts also in opposite directions to get the proper action upon the propellers at the stern of the torpedo.

By reference to Figure 1 it will be noted 85 that the driving wheel 10 is provided with a sleeve 18 and a concentric sleeve 20 is carried by the driven wheel 13 and between these wheels are a series of roller bearings 21 and ball bearings 22 to eliminate friction as much as possible. Interposed 90 between the sleeve of the driven wheel 13 and the spider 7 is another ball bearing 23. The parts are held in assembled position by means of locking collars 24 and 25 as may be 95 necessary.

All of these roller bearings and relatively moving parts are lubricated to reduce friction throughout the entire mechanism as much as possible. In order to prevent overheating of this lubricant it will be noted that the shell 26 housing the roller bearings is provided with an inlet 27 and an outlet 28, the latter communicating through pipe 30 as shown diagrammatically with the oil reservoir 31 which in turn communicates with the pump 32 leading to a cooling coil 33 within a chamber 34 which chamber is open to sea water at 35 and provided with an outlet 36. The coil 33 is provided with 100 a return pipe 37 leading back to the inlet opening 27.

During the run of the torpedo the pump is actuated in any desired manner to cause a circulation of the lubricant through the operating mechanisms thence to the cooling chamber prior to its return to the operating mechanism.

It will also be noted that the driven wheel is provided with a plurality of openings 38 and a flange 40 extending beyond a second flange 41 on the spider 7, these flanges, of course, being within the housing 26. Thus as the turbine rotates, any oil which may leak past the relatively moving sleeves towards the driven wheel is thrown out through these openings 38 and caught by the flange 41 and returned to the interior of the casing 26 where it joins the flow of circulating oil.

From the above it will be seen that the present invention contemplates a simple and practical power unit particularly adapted for use in the propulsion of torpedoes. Obviously the unit is much simpler than the disc turbine now in use and the avoidance of transmission gears greatly reduces weight and expense involved in construction and installation. The cooling and circulating of the lubricant through a water chamber will, of course, materially keep down the temperature of the turbine and thereby increase its efficiency and reliability.

What I claim is:—

1. In a torpedo, in combination, driving and driven turbine wheels, concentric driven shafts with which said wheels are connected, antifriction devices interposed between the relatively moving parts to reduce friction, a lubricating circulating system for forcing oil over the relatively moving parts, and a chamber through which sea water may automatically pass in transit of the torpedo through water, the chamber housing a portion of the lubricating system in the path of flow of the water therethrough.

2. In a torpedo, in combination, driving and driven turbine wheels, concentric driven shafts with which said wheels are connected, anti-friction devices interposed between the relatively moving parts to reduce friction and a lubricating circulating system for forcing oil over the relatively moving parts, means for cooling said oil during the operation of the device, said cooling means comprising a chamber open to sea water.

3. In a torpedo, in combination, driving and driven wheels, one of which is provided with a centrally disposed conduit connected with the source of power, two concentrically disposed driven shafts connected with the driving and driven turbines, a casing engaging a portion of said shafts, roller bearings between the relatively movable parts, forced feed lubricating means connected with said casing for lubricating the relatively moving parts, and means for cooling the lubricating system, said means comprising a chamber housing a portion of said system and through which sea water is caused to automatically pass by the forward movement of the torpedo.

4. In a torpedo, in combination, driving and driven wheels, one of which is provided with a centrally disposed conduit connected with the source of power, two concentrically disposed driven shafts connected with the driving and driven turbines, a casing engaging a portion of said shafts, roller bearings between the relatively movable parts, forced feed lubricating system for lubricating the relatively moving parts, said lubricating system including an oil reservoir, a pump and a cooling coil exposed to constantly changing sea water that is automatically forced about the coil by the progress of the torpedo through the water, the opposite ends of which are connected respectively with opposite sides of said casing.

5. In a torpedo, in combination, driving and driven wheels, one of which is provided with a centrally disposed conduit connected with the source of power, two concentrically disposed driven shafts connected with the driving and driven turbines, a casing engaging a portion of said shafts, roller bearings between the relatively movable parts, forced feed lubricating means for lubricating the relatively moving parts, said lubricating means including an oil reservoir, a pump and cooling coil, the opposite ends of which system are connected respectively with opposite sides of said casing, said cooling coil being disposed adjacent the shoulder of the torpedo and subject to the sea water through which the torpedo passes.

Signed at New York, N. Y., this 31 day of Dec., 1924.

ARTHUR F. BLASIER.
